[57] CLAIM

The ornamental design for a rear mounted mower for tractors, as shown and described.

DESCRIPTION

FIG. 1 is a perspective view showing the top and one side of the rear mounted mower for tractors;

FIG. 2 is a perspective view showing the top and the front thereof;

FIG. 3 is a perspective view showing the top and the rear thereof.

That side of the rear mounted mower for tractor opposite to the side shown in FIG. 1 is identical therewith and without further ornamentation.

FIG. 1

FIG. 2

FIG. 3
